Filed July 13, 1967, Ser. No. 7,789

Term of patent 14 years

(Cl. D34—5)

FIG. 3

FIG. 1

FIG. 2

FIG. 1 is a front view of a golf club grip showing my design;

FIG. 2 is a side view of the golf club grip; and

FIG. 3 is an end view of the golf club grip.

The characteristic features of my design reside in the combination on the club grip of a row of chevron-shaped grooves that are interconnected by a full length longitudinal groove extending through the apex of the chevrons alternating with a row of horizontal straight grooves, all as shown.

I claim:

The ornamental design for a golf club grip, as shown and described.
